UNITED STATES PATENT OFFICE.

HENRY FRALICK, OF GRAND RAPIDS, MICHIGAN.

FORGE APPLIANCE.

1,194,373.

Specification of Letters Patent. Patented Aug. 15, 1916.

Application filed March 25, 1915. Serial No. 17,020.

To all whom it may concern:

Be it known that I, HENRY FRALICK, a citizen of the United States of America, residing at Grand Rapids, in the county of 5 Kent and State of Michigan, have invented certain new and useful Improvements in Forge Appliances; and I do hereby declare the following to be a full, clear, and exact description of the invention, such as will enable others skilled in the art to which it 10 pertains to make and use the same.

This invention relates to appliances adapted to be used with forges.

It is the object and purpose of the invention to provide an appliance which may wholly or partly surround the fire in a forge and through which air may be forced at a plurality of points around the fire in an upward direction so as to carry the heat upward into the chimney or hood of the forge and prevent the radiation thereof outwardly from the fire to thereby protect operators working near the forge.

Further objects of the invention are to 25 provide a device of this character with various new and useful auxiliary improvements consisting in means for controlling the air supply; an attachment to the appliance whereby a twyer may be connected 30 thereto together with means for controlling the supply of air to the attachment; and in various other new and useful improvements as will more fully appear hereinafter, reference being had to the accompanying drawing, in which;

Figure 1 is a perspective view showing my improved appliance used in connection with a forge. Fig 2 is a plan view of a preferred form of forging appliance. Fig. 3 is a side 40 elevation thereof, a part being broken away to disclose the construction. Fig. 4 is a vertical sectional view taken through the bed of the forge; and Fig. 5 is a modified construction showing another form of the appliance. 45 Like reference characters refer to like parts throughout the several views of the drawing.

In the embodiment showing the invention, a forge is indicated at 1, the bed thereof being formed in the usual manner and containing fire clay or similar material 1^a in the bed through which projects the usual twyer 2, the air being conveyed to the twyer through a pipe 3 supplied by any suitable 55 blower such as indicated at 4. It is of

course understood that the type of blower is not an essential part of the invention. The hood 5 of the forge is placed in usual position above the twyer 2.

Interposed in the length of pipe 3 is a 60 branch 6 to which is connected a flexible conduit 7 preferably formed from rubber hose. My appliance is secured at the end of the conduit 7, it consisting of a tubular section 8 terminating in a substantial circular 65 tubular member 9. A plurality of openings 10 are formed in the member 9 on the inner and upper surface thereof through which air entering said member may escape. A valve 11 is provided in the section 8 and may be 70 operated to control the supply of air passing to the appliance. Similarly a valve 12 is interposed in the length of the pipe 3 to control the supply of air passing through the twyer 2. In the use of the appliance it 75 is placed around the fire which is built above the twyer 2. When the heat from the fire becomes too great for comfort, valve 11 may be turned to permit the passage of air through the openings 10. The position of 80 these openings is such that the normal flow of air therethrough is upward and slightly inward over the fire carrying the heat upward into the hood 5. In this manner no matter how large the fire may be one working near it will be protected from the heat.

Various modifications in the construction may be resorted to. For instance, I have shown an extension 13 substantially in line with the section 8 of the appliance and provided with a controlling valve 14. To this extension a twyer may be attached if desired, and positioned in a plane below the appliance 9 and the air may be taken directly from the blower 4 through the flexible 95 conduit 7 to said twyer. Similarly, valves 15 may be positioned one at either side of the extension 13, as shown in dotted lines, to shut off the air from the member 9 when desired or to permit the entrance of air to 100 either side thereof, a stop 16 being shown at a point diametrically opposed to the extension 13. By this modification in construction the air may be permitted to pass through only one side of the part 9 as in the 105 case where the fire becomes larger at one side than at another. Furthermore in Fig. 5 I have shown the slight modification in which two tubular arms project in opposite directions from the section 8 and provided 110

with the openings 10 as shown. With this modification it is intended that if any side of the fire should become larger than another so as to require protection for the operator at the forge, the device may be placed in position at said side to afford the desired protection. As a means to hold the device in any position to which it is placed I have secured, by means of a clip 18, the conduit 7 to a block 19 which has considerable weight and which when placed on the forge bed will hold the appliance in place. With this construction it will be readily understood that the excessive radiation of heat from a forge fire is insured against and protection afforded to one working around the forge. By reason of the flexible character of the conduit 7 the appliance may be moved at will and may at times be removed from the fire. For instance, many times in trip hammer work it is desirable that the scale coming from the forged metal be removed from the anvil as soon as it is freed from the metal worked upon. With a construction of this character and especially like that one shown in Fig. 5 the scale may be continuously blown away during the operation of the trip hammer. Various other uses will occur to those skilled in the art as well as various modifications in structure. My invention, however, comprehends all these

modifications in structure falling within the scope of the appended claims.

I claim:

1. An appliance for use with forges comprising a tubular section, a controlling valve in said section, a flexible conduit connected at one end of the section, tubular devices extending in opposite directions from the other end of the said section, and provided on their inner upper surfaces with a plurality of openings, and a block connected to the flexible conduit adjacent said tubular devices, substantially as described.

2. An appliance for use in forges comprising a tubular section, a controlling valve in said section, a flexible conduit connected at one end of the section, tubular devices extending in opposite directions from the other end of said section, controlling valves in each of said devices, a tubular extension projecting forward from said devices substantially in alinement with said tubular section and a controlling valve in the extension.

In testimony whereof I affix my signature in presence of two witnesses.

HENRY FRALICK.
